UNITED STATES PATENT OFFICE.

GEORGE E. NORRIS, OF COLUMBUS, OHIO.

COMBINATION AMUSEMENT AND VENDING DEVICE.

Application filed July 24, 1923. Serial No. 653,555.

To all whom it may concern:

Be it known that I, GEORGE E. NORRIS, a citizen of the United States, residing at Columbus, in the county of Franklin and State of Ohio, have invented certain new and useful Improvements in Combination Amusement and Vending Devices, of which the following is a specification.

The present invention is directed to improvements in combination amusement and vending devices.

The primary object of the invention is to provide a vending machine which is controlled by a toy pistol suitably connected with the vending machine casing, the construction of the pistol being such that a coin can be projected at a target located in the vending machine casing, said pistol having combined therewith a positive means for actuating the tripping mechanism of the vending machine so that a person operating a machine will be assured of a piece of confection, such as chewing gum, each time the pistol is operated.

A further object of the invention is to provide a novel form of pistol wherein the coin can be projected rapidly at a bull's eye and in this manner the skill of the operators can be ascertained, thereby affording considerable amusement when the machine is operated.

A further object of the invention is to provide means whereby only one coin can be inserted in the pistol at a time.

With these and other objects in view, as will appear as the description proceeds, the invention consists in the novel features of construction, combinations of elements and arrangements of parts, and hereinafter to be fully described and pointed out in the appended claims.

In the accompanying drawing:

Figure 1 is a side elevation of the device,

Figure 2 is a sectional view on line 2—2 of Figure 1,

Figure 3 is a side view of the pistol with one side plate removed,

Figure 4 is a sectional view on line 4—4 of Figure 3,

Figure 5 is a sectional view on line 5—5 of Figure 3,

Figure 6 is a detail sectional view of the vending mechanism trip,

Figure 7 is a front view of the vending tripping mechanism, partly in section, and

Figure 8 is a horizontal detail sectional view through the vending machine casing showing the vending pan.

Referring to the drawings 1 designates the stock of the pistol which consists of complementary sections 2 and 3, the forward ends of which terminate respectively in a plate 4 and a frame 5. The section 3 of the stock has pivotally connected thereto a hammer 6, the same being under constant tension through the medium of the suitably connected coil spring 7. The forward swinging movement of the hammer is limited by the stops 8 and 9. Slidable in a guide 10 formed between the plate 4 and the frame 5 is a bar 11, the rear end of which is provided with a trigger 12, while the forward end is formed with an offset lug 13 having an integral vertical pin 14 carried thereby and to which is pivotally connected the forward end of the detent 15. The rear end of the detent is provided with a shoulder 16 which is aligned with the shoulder 17 formed on the hammer 6 and is further provided with a beveled finger 18, the purpose of which will appear later. The shoulder 16 is slidable in a groove 19 in the frame 5 and in order to hold the detent 15 in yielding engagement with the frame a coil spring 20 is employed, one end of which being connected to a pin 21 carried by the frame 5, while the other end thereof is secured to the detent 15, and it will be observed that the spring is secured eccentrically to the pivotal connection of the detent with the pin 14 so as to assure that the detent will yieldably engage the associated frame.

The detent is further provided with a right angular lip 22 which overhangs the rib 23 of the frame 5, said rib being laterally spaced from the plate 4 so as to provide a coin receiving slot 24 which opens between the outer ends of the plate 4 and frame 5.

The plate 4 and frame 5 have suitably secured thereto cover plates 25 and 26, respectively. The cover plate 25 is provided with a groove 27 in which is located a longitudinally extending pin 28, the rear end of which is pivotally connected with the

hammer 6, as at 29, the purpose of which will appear later.

The cover plates are provided with diametrically disposed lugs 30 which are loosely mounted in the front wall 31 of the vending machine casing 32, said casing having located therein a target plate 33 with a bull's eye opening 34. Since the pistol is loosely mounted in the wall 30 the same may be sighted in order that the coin projected from the pistol may enter the opening 34, it being of course understood that the casing 32 will be equipped with suitable glass panels so that the pistol can be aimed and furnish sufficient light to the interior of the casing to discern the target.

Located behind the wall 35 which bears the target 33 is a spring controlled pivotally mounted plate 36 having a shoulder 37 carried thereby for normally engaging the spring controlled pivotally supported lever 38 to the upper end of which is pivotally connected a link 39, said link being also pivotally connected to a bar 40 which is pivotally connected intermediate its ends to a bracket 41 located in the casing 32, said bar having a pivoted pawl 42 carried by one end for successively engaging the ratchets 43 carried by the vending pan 44 to rotate the same so as to discharge one article at a time into the chute 45, the article vended being preferably sugar coated chewing gum in ball form, which finally are received in the discharge receptacle 46 carried by the casing.

In order to assure the person operating the machine a piece of gum or the like for each coin projected by the pistol, a rod 47 is employed and has its rear end located in the groove 27 of the pistol and in engagement with the forward end of the pin 28, the forward end of said rod being normally engaged with the plate 36, as more clearly shown in Figure 6 of the drawing. Thus it will be seen that every time the hammer 6 is actuated to project the coin from the pistol that the rod 47 will be actuated, thereby tripping the plate 36 to release the lever 38 whereupon the link 39 will swing the bar 40 to engage successively the ratchets 43 carried by the vending pan. To reset the lever 38 a handle 48 is slidably connected to one end of the bar 40 so that the player, upon moving the handle 48 outwardly, will swing the lever 38 to the position as shown in Figure 6 and simultaneously therewith, the pan will be rotated so that a ball of gum 49 will be discharged from one of its compartments into the chute 45 for delivery. Since the vending mechanism per se forms no part of the invention, and is of conventional form a detail description thereof is not thought necessary.

To operate the pistol a coin 50, shown in dotted lines in Figures 3 and 4 is dropped so as to occupy the space between the shoul-

der 16 of the detent and the shoulder 17 of the hammer so that when the trigger 12 is moved rearwardly the bar 11 and its associated detent 15 will slide rearwardly, and owing to the presence of the coin the hammer will be swung rearwardly as long as the coin serves as a connector. Continued movement of the bar 11 rearwardly will cause the beveled finger 18 of the detent to engage the cam 51 carried by the frame 5, thus causing the detent to swing laterally until the shoulder 16 thereof disengages the periphery of the coin; whereupon the coin will be projected from the pistol rapidly under the impact of the hammer 6. It will be of course obvious that as soon as the trigger 12 is released that the spring 20 will cause the bar and its associated detent to move forwardly to its normal or inactive position. Since the lip 22 is carried by the detent it will be obvious that the same will ride under the main coin slot entrance 52 so that a second coin can not be dropped into the pistol.

In using the device the operator grasps the stock 1 of the pistol and aims the same so that the coin projected will enter the bull's eye opening 34, and when this occurs the coin will gravitate and hit a bell 53 mounted in the casing so as to indicate that the coin has entered the bull's eye opening. Any coins not entering the opening 34 will drop down upon the chute 54 and into the casing, it being of course understood that the person using the pistol will receive an article whether the coin enters the opening 34 or not, this being accomplished through the medium of the rod 47 which trips the vending mechanism every time the hammer actuates to project the coin from the pistol.

A coil spring 55 is employed and has one end connected to the outer end of the rod 47 while its other end is anchored to the casing in any suitable manner, said spring serving to assure that the rod 47 will be normally engaged with the pin 28.

When the plate 4 and frame 5 are in their assembled relationship and the cover plates 25 and 26 are attached thereto, a barrel 56 will be simulated so that the pistol will have the general appearance of a real pistol.

What is claimed is:

1. A pistol of the class described comprising a barrel, a spring actuated hammer associated with the barrel, a trigger having a bar carried thereby, a detent pivotally connected with the bar, the barrel having an entrance slot to permit a coin to be placed between the detent and hammer, and means for swinging the detent laterally when the trigger bar is actuated to release the coin, whereby the hammer propels the coin from the barrel.

2. A pistol of the class described comprising a barrel, a spring actuated hammer as-

- sociated with the barrel, a detent slidably mounted in the barrel, means for inserting a coin between the detent and hammer, and means for sliding the detent rearwardly and 5 swinging the same laterally to permit the hammer to propel the coin from the barrel.
3. A pistol of the class described comprising a barrel, a spring actuated hammer associated with the barrel and having a shoulder, a bar slidable in the barrel and having a trigger carried thereby, a detent pivotally connected with the bar, said detent having a shoulder, means for inserting a coin in the barrel for engagement between the shoulders 10 of the detent and hammer, and means operable upon sliding the bar and trigger rearwardly to move the detent laterally to cause the shoulder thereof to disengage the coin, whereby the hammer is operated to project 15 the coin from the barrel.
4. A pistol of the class described comprising a barrel, said barrel having a coin slot therein, a trigger bar slidable in the barrel and having a detent pivotally connected therewith, a shoulder on the detent and normally engaged in the coin slot, a spring actuated hammer pivotally associated with the barrel and having a shoulder normally aligned with the shoulder of the detent, 20 means for inserting a coin in the barrel for lodgement between the shoulders of the hammer and detent, and means for swinging the detent laterally to free the shoulder of the detent from the coin to permit the hammer 25 to propel the coin from the coin slot.
5. A toy pistol of the class described comprising a barrel, a hammer associated with the barrel, a detent in the barrel for engagement with a coin positioned between the 30 hammer and a detent, and means for sliding the detent rearwardly to place the hammer in a coin propelling position, and means for 35
- swinging the detent laterally to free the coin to permit the hammer to project the same from the barrel. 40
6. In combination with a vending machine, a pistol, a hammer for the pistol, and means connecting the vending mechanism and hammer and operable by the hammer for actuating the vending mechanism upon 45 actuation of the hammer.
7. In combination with a vending machine, a pistol, a trigger actuated bar associated with the barrel and having a detent carried thereby, means for introducing a coin in the barrel for connecting the hammer and detent, a pin having one end pivotally connected with the hammer, a rod engaged with the other end of the pin for actuating the vending mechanism when the 50 hammer is disengaged from the coin, and means for swinging the detent laterally to permit the release of the coin. 55
8. In combination with a vending machine, a pistol comprising a barrel, a hammer associated with the barrel for projecting a coin therefrom, a pin slidably associated with the barrel and pivotally connected with the hammer for actuating the vending mechanism upon actuation of the 60 hammer, as and for the purpose set forth. 65
9. A pistol of the class described comprising a barrel, having coin entrance and exit slots, a spring actuated hammer associated with the barrel, a detent slidably and pivotally mounted in the barrel for cocking the hammer when a coin is placed between the detent and hammer, and means carried by the detent for obstructing the coin entrance slot when the detent is in a hammer cocking 70 position. 75

In testimony whereof I affix my signature.

GEORGE E. NORRIS.
